CLAIM

The ornamental design for game controller for mobile devices as shown and described.

DESCRIPTION

FIG. 1 is a perspective view illustrating a game controller for mobile devices, showing my new design;

FIG. 2 illustrates a front side of the design;

FIG. 3 illustrates a back side of the design;

FIG. 4 illustrates a left side of the design;

FIG. 5 illustrates a right side of the design;

FIG. 6 illustrates a top side of the design; and,

FIG. 7 illustrates a bottom side of the design.

The broken lines shown in FIGS. 1-7 illustrate the environmental structure of the game controller for mobile devices that form no part of the claimed design.
